(57) **CLAIM**

The ornamental design for a golf club head, as shown and described.

DESCRIPTION

FIG. 1 is a top perspective view of a golf club head; FIG. 2 is a bottom perspective view of the golf club head of FIG. 1; FIG. 3 is a front elevational view of the golf club head of FIG. 1; FIG. 4 is a rear elevational view of the golf club head of FIG. 1; FIG. 5 is a top view of the golf club head of FIG. 1; FIG. 6 is a bottom view of the golf club head of FIG. 1; FIG. 7 is a left side view of the golf club head of FIG. 1; and, FIG. 8 is a right side view of the golf club head of FIG. 1. The broken lines shown on the drawings form no part of the claimed design. The dash-dotted lines are included as boundary lines and form no part of the claimed design. Portions of the golf club head are stippled heavier and lighter to illustrate contrasting surfaces of different color.
